(57) **CLAIM**

The ornamental design for a hair clipper, as shown and described.

DESCRIPTION

FIG. 1 is a front perspective view of the hair clipper showing my new design;

FIG. 2 is a front view of the hair clipper of FIG. 1;

FIG. 3 is a top plan view of the hair clipper of FIG. 1;

FIG. 4 is a left side view of the hair clipper of FIG. 1;

FIG. 5 is a right side view of the hair clipper of FIG. 1;

FIG. 6 is a rear view of the hair clipper of FIG. 1; and,

FIG. 7 is a bottom plan view of the hair clipper of FIG. 1. The cord portion partially illustrated by broken lines in FIGS. 1-3, 5 and 6 forms no part of the claimed design.
